UNITED STATES PATENT OFFICE.

GEORGE W. BRANDT, OF BROOKLYN, NEW YORK, ASSIGNOR TO MARY E. BRANDT, OF LEONIA, NEW JERSEY.

CONSTRUCTION OF FORMS FOR CONCRETE CONSTRUCTION.

1,112,112.

Specification of Letters Patent. Patented Sept. 29, 1914.

Application filed December 30, 1910. Serial No. 600,205.

To all whom it may concern:

Be it known that I, GEORGE W. BRANDT, a citizen of the United States, residing at 792 De Kalb avenue, Brooklyn, in the county of 5 Kings and State of New York, have invented a new and useful Construction of Forms for Concrete Construction, of which the following is a specification.

My invention relates to the process of 10 holding concrete in continuous (either vertical or horizontal) sectional, adjustable plank forms with a series of cores, until it sets and has for its object to render the process more expeditious and damp proof, 15 it being a hollow, air circulating construction and considerably cheaper, as it requires less materials and less labor than the methods now employed. I attain these objects by the mechanism illustrated in the accompanying drawings. In casting concrete in 20 these forms, I employ wood, with series of holes through the wood, with steel plates over the holes on one side of each side form and bolts to pass through the plate and form 25 on the one side and screw into the plate on the outside of the other side form, with wood cores set between the series of bolts.

Figure 1. is a vertical section of a mass of forms locked together. Fig. 2. is an end 30 view through the forms, showing the bolts through and holding the sides of forms together. Fig. 3. is a side view of two side forms horizontally locked together. Fig. 4. is a top view of Fig. 3. forms. Fig. 5. is a 35 top view of a set of forms with doweled partitions set. Fig. 6. is a vertical side view of a locked mass of forms set for vertical casting of concrete formation. Fig. 7. is an end view of Fig. 6. Fig. 8. is a side view of a 40 single set of side forms set on a finished hollow course of wall (Fig. 9.) ready to cast the second course of wall. Fig. 9. is the end view of Fig. 8., showing an end view of the opposite side and core. Fig. 10. shows the 45 end of finished hollow wall (Fig. 11.), before the forms and cores are removed from the concrete. Fig. 11. is a top view of a finished piece of hollow wall with forms and cores removed. Fig. 12. is an end view of a 50 finished wall, cast with forms set vertically. Fig. 13. is a top view of a ninety degree angle form with horizontal and vertical cores partially set. Fig. 14. is a top view of a forty-five degree angle form with horizontal 55 and vertical angle cores set. Fig. 15.

is a top view of a part of a circle corner form with a ninety degree angle. Fig. 16. is a top view of a part of a circle corner connected to the regular running forms. Fig. 17. is a side of the self-supporting core. 60 Fig. 18. is an end view of the vertical and horizontal core. Fig. 19. is a bottom view of Fig. 17. with horizontal core attached thereto. Fig. 20. is an end view of the horizontal cores. Fig. 21. is a side view of the 65 hinged horizontal cores. Fig. 22. is a top view of circular formation forms. Fig. 23. is a side view of an arch formation sprung from piers with all forms removed. The dotted lines show reinforcing steel work and 70 metal soffit. Fig. 24. is a side view of arch (Fig. 23.) before the side forms and partitions to form piers and arch are removed. The dotted lines show partitions, also sprung steel and metal soffit from pier to 75 pier.

Similar letters refer to similar parts throughout the several views.

The sides A. constitute the main plank body of forms, its steel plates B. and B. B. 80 sunken in flush across the sides of forms and fastened thereto, with its spaced holes C. C. drilled for bolts C' to pass through plate B. and plank and through the opposite plank form and screwed into the tapped plate B. B. 85 secured to it (Fig. 2.), which holds the plank sides A. to a width apart, to cast the required thickness of concrete. Holes d. in sides A. are for partition adjustments (Fig. 5.). Drilled steel plate F., similar to B. previously referred to, forms the lock over joints of plates B. by passing the bolts C' through plate F. then through holes C. C. and securing with a lock nut on ends of bolts C' after it passes through the opposite side 90 form and tapped plate B. B. and steel plate F. (Fig. 2.). The nuts K. are the lock nuts on the end of bolts C' to secure strap lock F. (Fig. 2.).

The vertical cores H. are supported centrally between the side forms A. by the steel plates J., pivotally secured to the cores by ring bolts M. and resting on the top edge of the side forms A. with the ends turned down in the channel N. on the edge of side forms 100 (Fig. 13.), also the horizontal hinged core H. H. attached to the vertical core H. rests on the lower line of bolts C'. and intermediate walls which support it and hold same 105 centrally in and on the intermediate walls 110

(Figs. 9, 10, 11, 17.). They are lifted out by steel ring bolts M. secured to cores through steel plates J.

The horizontal core H. H. is constructed 5 into three (3) parts and secured together by steel hinges O. and supported by the center portion P. of the three parts which is permanently attached to the vertical core H. and the outer ends H. H. resting on the lower 10 line of bolts C.' of the side forms A. is lifted out of the concrete construction with the cores H., the part P. remaining horizontal, allowing the outer parts H. H. to drop down vertically and clear the intermediate wall.

15 The angle sides of forms A. are secured at their intersecting points by hinges L. (Figs. 13, 14 and 15.). The circle corner forms are secured by the metal sheathing R., being secured to the circle side forms A. and then 20 running past the intersection of the circle and the straight side forms A. to the first line of holes in the side forms A., so that bolts C.' will pass through the series of corresponding holes in the metal sheathing.

25 The arch (Fig. 24.) are the regular running side forms A. In the forming of an arch by them, when piers are built to the required height, the forms A. are left in place, bolted to the piers, also the partitions E., 30 one or more side forms A. are then placed thereon, as needed for raise of arch centrally and its height of finish. The sprung steel S. is then set inside of forms A., resting on piers and covered with metal T. from inside 35 to inside of forms A. to line of piers at spring of arch, making support for concrete arch formation. The dotted lines U. indicate steel reinforcement built in arch, as usually required, but has no other meaning 40 in regard to construction of arch. The partitions may be set in any two holes in the side forms, either the two center holes in the side forms, the two upper holes, or the two lower holes, as may be required to form a 45 pier, a stop in a running line of wall, or to make provision for reinforcing irons that may be required to run over any one or more partitions.

I attain angles by hinged forms which 50 will connect on either end of any length of the regular straight forms. I attain circular formation by the part of a circle desired sawed out of wood as a form and lined with metal containing a series of holes that will 55 connect on either end of any running length of the regular straight forms with bolts C.

I attain arch formation by using the reinforcing sprung steel resting on a wall or pier inside of the regular forms and covering same with metal or wire to form the soffit which takes the place of a center, as 60 usually done, the reinforcing steel, metal or wire being left in as a reinforcement of the concrete construction. I attain the girder and beam formation from pier to pier or wall to wall by the forms being suspended 65 by any line of bolts resting on the top of the girder or beam, being incased, as would be required; and a plank resting on any line of bolts, as required to form the bottom of the forms. I attain the vertical concrete 70 formation by incasing the already constructed work within the regular forms standing on end locked together, as the regular straight forms, with planks resting against any line of bolts, as may be required to form 75 the other two required sides. I attain the vertical circular formation by plank staves with circular steel plates fastened to the staves with a series of holes and made in two parts and held together with bolts, as 80 the regular forms, using similar drilled plates as locks, as regular straight forms A. (Figs. 3. and 22.). I attain the horizontal air circulation by connecting the vertical with the horizontal air chambers at the bottom and top of the constructed work when 85 started and finished, also at every course, as may be desired.

I am aware that, prior to my invention, block molds have been invented to form concrete blocks. I therefore do not claim such a combination broadly, but 90

I do claim:

In a mold to form a ventilated concrete structure the combination comprising side 95 framings, a core to suspend between the framings to produce the vertical ventilating shafts, straps across the framing and flanges on the ends of the straps, ring hooks suspending the said core from the said straps, 100 and hinged horizontal extensions on the bottom of said core, the extensions projecting beyond the bottom ends of the core to connect with adjacent horizontal core extensions to make continuous horizontal passages 105 opening into the vertical shafts.

GEORGE W. BRANDT.
